COMBINED WASHING MACHINE AND SPIN TUB WITH ONE-WAY FLUID DRIVE

John C. Sharp, Glen Ellyn, Ill., assignor to General Electric Company, a corporation of New York

Application December 10, 1949, Serial No. 132,287

4 Claims. (Cl. 68—23)

1

The present invention relates to clothes washing machines, and more particularly to such machines of the spin tub type incorporating fluid drive mechanism for rotating the tub.

A clothes washing machine of the type noted usually comprises an upstanding casing, an upstanding tub arranged in the casing and mounted for rotation, and an upstanding agitator arranged in the tub and mounted for oscillation. A water supply system communicates with the tub, and a drain conduit communicates with the casing; water is supplied from the system into the tub for filling and rinsing purposes, and excess water that is supplied to the tub is overflowed therefrom and caught in the casing. In order to effect extraction of the wash water and the rinse water from the tub and the clothes contained therein, the tub is spun or rotated, whereby the water is centrifuged from the tub and the clothes contained therein and caught in the casing. The water that is caught in the casing is discharged via the drain conduit to the exterior.

Ordinarily the clothes washing machine further comprises two electric motors that are employed respectively to oscillate the agitator and to rotate the tub. More particularly, motion translating mechanism is driven by a first of the motors and the agitator is driven by the motion translating mechanism, rotary motion being translated into oscillatory motion in the motion translating mechanism. Clutch mechanism is arranged between the motion translating mechanism and the agitator so that the agitator may be selectively operated during washing and rinsing operations as required in the operation of the machine. Also, a drain pump is driven by the first motor and arranged to discharge the water through the drain conduit to the exterior under pressure. Finally, a fluid drive unit is arranged between the second of the motors and the tub in order to accommodate slippage therein between the second motor and the tub. This arrangement of the fluid drive unit not only insures smooth and gradual acceleration of the tub in response to initiation of operation of the second motor, but it also permits the tub to be rotated at a lower than normal speed in the event of an abnormal unbalance of the tub during a water extracting operation should the clothes in the tub become bunched, or otherwise unevenly distributed therein.

While the clothes washing machine of the type described is entirely satisfactory in operation, it

2

is somewhat more expensive to manufacture than is desirable, due primarily to the provision therein of the two electric motors.

Accordingly, it is a general object of the present invention to provide a clothes washing machine of the type described that incorporates improved power transmission mechanism that is selectively operative by a single electric motor to perform the various washing and rinsing and water extracting operations as required in the cycle of operation of the machine.

Another object of the invention is to provide in a clothes washing machine of the type described, an improved power transmission mechanism that is driven by a single electric motor of the reversible type and which is so organized that rotation of the rotor of the motor in opposite directions is employed to control selective rotation of the tub and to control selective oscillation of the agitator.

A further object of the invention is to provide in a clothes washing machine of the type described, an improved and simplified electric control arrangement for the electric motor that is of the split-phase, reversible rotor type, wherein the electric control arrangement is so organized that starting of the rotor of the motor in the proper direction and reversal of the direction of rotation of the rotor of the motor as required are positively insured.

Further features of the invention pertain to the particular arrangement of the elements of the clothes washing machine and of the electric control system therefor, whereby the above-outlined and additional operating features thereof are attained.

The invention, both as to its organization and method of operation, together with further objects and advantages thereof, will best be understood by reference to the following specification taken in connection with the accompanying drawings, in which Figure 1 is a vertical sectional view, partly broken away, of a clothes washing machine embodying the present invention, this view being taken through the vertical center line of the machine along a plane substantially parallel to the front and rear walls of the casing thereof; Fig. 2 is another vertical sectional view, partly broken away, of the clothes washing machine, taken in the direction of the arrows along the offset line 2—2 in Fig. 1; Fig. 3 is a horizontal sectional view of the lower portion of the clothes washing machine, taken in the direction of the arrows along the offset line 3—3 in Fig. 1; Fig. 4 is a diagram-

matic illustration of the electric control arrangement for the clothes washing machine, as well as a schematic chart of the timed cycle of operation thereof; Fig. 5 is an enlarged vertical sectional view of a fluid drive unit that may be incorporated in the clothes washing machine illustrated in Figs. 1 to 4, inclusive; Fig. 6 is a further enlarged fragmentary vertical sectional view of the fluid drive unit shown in Fig. 5, this view being taken in the direction of the arrows along the line 6—6 therein; Fig. 7 is an enlarged vertical sectional view of a modified form of the fluid drive unit that may be incorporated in the clothes washing machine illustrated in Figs. 1 to 4, inclusive; and Fig. 8 is a further enlarged fragmentary vertical sectional view of the fluid drive unit shown in Fig. 7, this view being taken in the direction of the arrows along the line 8—8 therein.

Referring now to Figs. 1 to 3, inclusive, of the drawings, there is generally illustrated a clothes washing machine 10 of the oscillating agitator and rotating tub type embodying the present invention. Specifically, the machine 10 is of the general construction and arrangement of that disclosed in U. S. Patent No. 2,513,845, granted on July 4, 1950, to George P. Castner and Arthur D. Lund, and comprises an upstanding casing 11 including upper and lower sections 12 and 13, the casing sections 12 and 13 being suitably detachably secured together, a surrounding gasket 14 formed of rubber, or the like, being disposed at the junction therebetween. The casing sections 12 and 13 are generally square in horizontal cross section with rounded corners connecting the various walls thereof. The upper casing section 12 is supported directly upon the lower casing section 13; and the lower casing section 13 is supported upon four vertically adjustable feet 15 respectively arranged at the four rounded corners thereof and respectively engaging four mounting pads 16 formed of linoleum, or the like, and suitably secured to a floor or other external support. The upper casing section 12 includes front and rear walls 17 and 18, side walls 19 and 20, and top and bottom walls 21 and 22; while the lower casing section 13 includes front and rear walls 23 and 24, side walls 25 and 26, and a bottom wall 27. Thus the bottom wall 22 of the upper casing section 12 constitutes a dividing wall between the upper and lower casing sections 12 and 13; whereby the upper casing section 12 defines a tub and water receiving compartment 28, and the lower casing section 13 defines a machinery compartment 29.

Within the machinery compartment 29 there is disposed a frame 30 upon which the principal component elements of the apparatus are mounted, the frame 30 being provided with a substantially centrally disposed and downwardly directed foot 31 arranged in an associated bearing 32, that is, in turn, supported by a resilient bushing 33 formed of rubber, or the like, and disposed in a depression 34 formed in the bottom wall 27 of the lower casing section 13. The frame 30 is thus resiliently supported for limited longitudinal movement in the vertical direction and is also capable of limited gyratory or wobbling movement about the longitudinal axis of the machine 10. In order to center the frame 30 along the longitudinal axis of the machine 10 and in its upstanding position, four radially extending and angularly spaced-apart tension springs 35 are arranged below the bottom wall 22 of the upper casing section 12 and

extend between four posts 36 carried by the frame 30 and four adjustable eye bolts 37 carried by four brackets 38 that are secured to the walls of the lower casing section 13 adjacent to the four rounded corners between the front and rear walls 23 and 24 and the side walls 25 and 26. Also, in order to limit the gyratory movement of the frame 30 about the foot 31 and about the longitudinal axis of the machine 10, four radially extending and angularly spaced-apart snubbers 39 are provided between the frame 30 and four brackets 40 respectively secured to the front and rear walls 23 and 24 and the side walls 25 and 26 of the lower casing section 13.

The frame 30 carries an upstanding longitudinally extending barrel 41 projecting from the machinery compartment 29 through an opening 42 provided in the central portion of the bottom wall 22 into the tub compartment 28, the opening 42 being surrounded by an upstanding tubular sleeve 43 arranged in spaced relation to the barrel 41 and joined to the bottom wall 22. Within the barrel 41 there is mounted a rotatable sleeve 44, the upper and lower ends of the sleeve 44 being suitably journalled upon upper and lower anti-friction bearings 45 and 46 arranged within the respective upper and lower ends of the barrel 41. The upper end of the sleeve 44 terminates in an annular flange 47 to which there is secured by a number of bolts 48 an upstanding tub 49, the tub 49 being arranged entirely within the tub compartment 28. The lower end of the sleeve 44 has rigidly secured thereto a pulley 51 arranged within the machinery compartment 29. Thus, it will be understood that when the pulley 51 is rotated that the sleeve 44 is rotated effecting rotation of the tub 49. The tub 49 comprises a substantially centrally disposed downwardly extending conical bottom element 52 terminating in an annular sediment trap structure 53. Also, the tub 49 includes an outwardly directed bottom wall 54 surrounding the annular trap structure 53 and merging into an upwardly tapered side wall 55, a heavy balance ring 56 being secured to the upper edge of the side wall 55. The balance ring 56 is provided with an inwardly directing flange 57 having a substantially centrally disposed opening 58 formed therein for the purpose of rendering the interior of the tub 49 accessible from the exterior, the flange 57 preventing clothes from being flung from the tub 49 incident to rotation thereof. The lower portion of the balance ring 56 is provided with a number of serrations in order to define a number of openings 59 between the lower portion thereof and the upper edge of the side wall 55 of the tub 49 in order to accommodate the passage of water therethrough as a result of the centrifugal forces when the tub 49 is rotated. Further, two outwardly and then upwardly extending tubes 60 are carried upon the exterior of the tub 49 at substantially diametrically disposed positions, the lower ends of the tubes 60 communicating with the sediment trap structure 53 and the upper ends of the tubes 60 discharging into cooperating grooves 61 formed in the balance ring 56 and communicating with the tub compartment 28. Further, it is pointed out that the sediment trap structure 53 comprises an inwardly directed throat or flange member 62 joining the bottom wall 54 of the tub 49 and overhanging the lower ends of the tubes 60. It will be understood that any sediment accumulating in

the sediment trap 53 will be discharged through the tubes 60 into the tub compartment 28 incident to rotation of the tub 49 as a consequence of the centrifugal forces produced.

A longitudinally extending upstanding shaft 63 is suitably journaled in a centrally disposed opening formed in the sleeve 44, the upper end of the shaft 63 projecting through a tubular extension 64 carried by the conical bottom element 52 of the tub 49. The upper end of the shaft 63 is journaled in and supported upon a bearing element 65 arranged in the upper end of the tubular extension 64; and the lower end of the shaft 63 is located with respect to the lower end of the sleeve 44 by a bearing 50 that is positioned by a collar 50a which is detachably secured to the lower end of the shaft 63. The extreme upper end of the shaft 63 has detachably secured thereto by a fixture 66 an upstanding bladed agitator 67 arranged in the tub 49 and surrounding the tubular extension 64. The agitator 67 includes a substantially conical shaped body 68 terminating in an annular flange 69 disposed over the inwardly directed throat member 62. The lower end of the body 68 of the agitator 67 carries three upstanding angularly spaced-apart main clothes agitating blades 70; and the upper end of the body 68 of the actuator 67 carries three intervening angularly spaced-apart auxiliary suds agitating vanes 71. The junction between the main vanes 70 and the auxiliary vanes 71 on the agitator 67 being arranged adjacent to the normal water level in the tub 49 indicated by the dash line 72.

Also the frame 30 carries an oscillating mechanism 73 that is preferably of the character of that disclosed in U. S. Patent No. 1,964,440, granted on June 26, 1934, to Allen J. Patch. The oscillating mechanism 73 includes a casing 74 in which there is journaled an upstanding shaft 75 that projects therethrough. The shaft 75 carries a crank arm 76 that is oscillated by associated parts, not shown. The shaft 75 is arranged along the longitudinal axis of the machine 10 coincident with the longitudinal axis of the shaft 63; and clutch mechanism 77 is interposed between the upper end of the shaft 75 and the lower end of the shaft 63. Specifically, the clutch mechanism 77 comprises cooperating clutch elements 78 and 79 respectively carried by the upper end of the shaft 75 and by the lower end of the shaft 63. The clutch element 78 is splined upon the upper end of the shaft 75 for longitudinal sliding movement thereon toward and away from the cooperating clutch element 79 rigidly secured to the lower end of the shaft 63 in order to effect engagement and disengagement of the clutch elements 78 and 79. The mechanism 77 further comprises a bell crank 80 carried by the frame 30, one end of the bell crank 80 cooperating with the clutch element 78, and the other end of the bell crank 80 cooperating with the armature of a solenoid 81, also carried by the frame 30. It will be understood that when the solenoid 81 is energized the bell crank 80 is operated to clutch the elements 78 and 79; and when the solenoid 81 is de-energized the bell crank 80 is returned to its normal position in order to declutch the elements 78 and 79. When the clutch mechanism 77 occupies its clutched position the oscillating mechanism 73 effects oscillation of the shaft 63 and the consequent oscillation of the agitator 67 with respect to the tub 49.

Further, the frame 30 carries within the ma-

chinery compartment 29 a single electric motor 201 that is of the split-phase reversible rotor type, the motor 201 including a main winding and a starting winding, as explained more fully hereinafter, as well as a rotor, not shown, that is carried upon an operating shaft 202. The operating shaft 202 carries a structure on the upper end thereof providing two pulleys 206 and 207. Also, the frame 30 carries a drain pump 10 86 that is provided with a casing 86' and a rotor, not shown, that is mounted upon an operating shaft 87, the operating shaft 87 carrying a pulley 88 on the upper end thereof. The pulley 206 carried by the operating shaft 202 of the motor 15 201 is belted by a V-belt 208 to the pulley 88 carried by the operating shaft 87 of the drain pump 86; and the pulley 207 carried by the operating shaft 202 of the motor 201 is belted by a V-belt 209 to a pulley 91 secured to an operating shaft 74' extending into the upper portion of the casing 74 of the oscillating mechanism 73. Thus, it will be understood that when the motor 201 is operated, the drain pump 86 is operated, and also the operating shaft 74' of the oscillating mechanism 73 is rotated; however, oscillation of the shaft 63 and the agitator 67 by the oscillating shaft 75 of the operating oscillating mechanism 73 are dependent upon the position of the clutch mechanism 77. It will be understood 20 that the oscillating mechanism 73 constitutes motion translating mechanism converting rotation of the operating shaft 74' into oscillation of the operating shaft 75 as disclosed in the Patch patent mentioned. Also, the drain pump 86 includes an intake connection 92 and a discharge connection 93. The intake connection 92 is suitably connected by a section of hose 92' formed of rubber, or the like, to a downwardly directed drain connection 94 provided in the 25 bottom wall 22 of the upper casing section 12; and the discharge connection 93 is suitably connected to a discharge conduit 95 projecting through an opening 96 formed in the rear wall 24 of the lower casing section 13. The drain pump 86 is so constructed and arranged that when the rotor, not shown, thereof is rotated in either direction, any water accumulating in the upper casing section 12 will pass through the drain connection 94 and the hose 92' into the intake connection 92 and will be pumped from the casing 96' through the discharge connection 93 via the drain conduit 95 to the exterior of the machine 10.

Further, within the machinery compartment 29 and upon the extreme upper end of the operating shaft 202 of the motor 201 there is mounted a fluid drive or coupling unit 200 disclosed more fully hereinafter. The fluid drive unit 200 includes a casing 214 that is selectively rotated 30 depending upon the direction of rotation of the operating shaft 202 of the motor 201, the casing 214 being rotated when the operating shaft 202 is rotated in the counterclockwise direction, as viewed from the top of the machine 10, and the casing 214 remaining stationary when the operating shaft 202 is rotated in the clockwise direction, as explained more fully hereinafter. The casing 214 carries a pulley 217 on the lower portion thereof that is connected by a V-belt 218 to the pulley 51 that is carried by the sleeve 44. Thus it will be understood that when the operating shaft 202 of the motor 201 is rotated in the counterclockwise direction, as viewed from the top of the machine 10, the casing 214 of the fluid drive unit 200 is rotated effecting rotation of the

pulley 217 and the consequent rotation of the sleeve 44 through the V-belt 218, whereby the tub 49 is rotated with the sleeve 44 in the counterclockwise direction. As previously noted, the fluid drive unit 200 insures gradual acceleration of the tub 49 to its full spinning speed when rotation of the operating shaft 202 of the motor 204 is initiated in the counterclockwise direction, and also permits an automatic slow-down of the tub 49 in its spinning operation in the event it contains an unbalanced load of clothes, or in the event the clothes are otherwise bunched or unevenly distributed in the tub 49 during rotation thereof.

The top wall 21 of the upper casing section 12 has a substantially centrally disposed square opening 104 formed therein in order to render the interior of the tub 49 accessible from the exterior of the machine 10, the opening 104 being surrounded by a downwardly directed substantially square flanged throat 105 preventing the presentation of sharp edges. The opening 104 formed in the top wall 21 is surrounded by a counterdepression 106 of substantially square form that receives an associated hinged cover 107, the cover 107 being hinged adjacent to the rear portion of the counterdepression 106 in any suitable manner, not shown. Thus it will be understood that the cover 107 in its closed position closes the opening 104 in the top wall 21, and in its open position permits ready access to the interior of the tub 49 through the opening 104 formed in the top wall 21. Also, the rear wall 18 and the rear portion of the top wall 21 of the upper casing section 12 carry a substantially L-shaped hood 108 in which there is arranged an inlet conduit 109, the front end of the inlet conduit 109 projecting through a hole 110 formed in the top wall 21 and overhanging the adjacent upper edge of the tub 49. The rear end of the inlet conduit 109 is connected by a suitable length of hose 111 formed of rubber, or the like, to inlet valve mechanism 112 disposed within the machinery compartment 29, the hose 111 passing through a hole 113 formed in the rear wall 24 of the lower casing section 12.

The inlet valve mechanism 112 comprises a casing 114 that is provided with a cold water inlet connection 119 and a hot water inlet connection 120, the connections 119 and 120 projecting through the hole 96 formed in the rear wall 24 of the lower casing section 13. Further, the casing 114 is provided with an outlet connection, not shown, that is connected to the lower end of the hose 111. The connections 119 and 120 are respectively connected to suitable sources of cold water and hot water associated with the laundry room in which the machine 10 is located, while the drain conduit 95 is associated with drain plumbing in the laundry room mentioned. The casing 114 further comprises a cold water chamber communicating with the cold water inlet connection 119, a hot water chamber communicating with the hot water inlet connection 120, and a mixing chamber communicating with the outlet connection that is connected to the lower end of the hose 111. The cold water chamber and the hot water chamber may be selectively opened and closed with respect to the mixing chamber by a cold water valve, not shown, and a hot water valve, not shown, respectively selectively operated by a cold water valve solenoid 128 and by a hot water valve solenoid 129. The detailed structure of the inlet valve mechanism 112 is not illustrated in the interest of brevity, but it will

be readily understood that the cold water valve and the hot water valve are normally biased into their closed positions and are respectively operated into their open positions in response to energization of the cold water valve solenoid 128 and the hot water valve solenoid 129. When the cold water valve solenoid 128 alone is energized cold water is supplied via the cold water inlet connection 119 through the inlet valve mechanism 112 into the tub 49; when the hot water valve solenoid 129 alone is energized hot water is supplied via the hot water inlet connection 120 through the inlet valve mechanism 112 into the tub 49; and when both of the solenoids 128 and 129 are energized both hot water and cold water are supplied via the respective connections 119 and 120 to the inlet valve mechanism 112 so that the resulting mixing causes warm water to be supplied to the tub 49.

For the purpose of controlling the various operations of the machine 10, a single manually operable control dial 130 is carried by the top wall 21 adjacent to the rounded corner at the junction between the rear wall 18 and the left-hand side wall 20 of the upper casing section 12, and a program selector switch 131 is arranged in the machinery compartment 29 and supported upon a bracket 132 carried by the left-hand side wall 26 of the lower casing section 13. The manually operable control dial 130 is operatively connected to the program selector switch 131 by an arrangement including a longitudinally extending control rod 133 projecting through the tub compartment 28. More particularly, a longitudinally extending tube 134 surrounds the control rod 133, the upper and lower ends of the tube 134 being securely anchored in upper and lower grommets 135 and 136 respectively secured in openings respectively formed in the top wall 21 and in the bottom wall 22 of the upper casing section 12. The grommets 135 and 136 are formed of rubber, or the like, and are sealed in liquid-tight relation in the openings respectively formed in the top wall 21 and in the bottom wall 22 and to the respective upper and lower ends of the tube 134 in order positively to insure fluid-tight joints and to render passage of the control rod 133 through the tub compartment 28, out of contact with any water contained therein. The lower end of the control rod 133 projects into the machinery compartment 29 and receives a fixture 137 that is, in turn, secured by an insulating sleeve 138 to an operating shaft 139 projecting from a casing 140 with which the program selector switch 131 is provided.

The manually operable control dial 130 comprises an upper knob portion 141 and a lower skirt portion 142, the extreme upper end of the control rod 133 being threaded into an opening provided in the body of the control dial 130. In passing it is noted that the manually operable control dial 130 is readily rotatable in the clockwise direction, as viewed from the top of the machine 10, but is unscrewed from the extreme upper end of the control rod 133 in the event rotation thereof in the counterclockwise direction is attempted. Thus the manually operable control dial 130 must be rotated in the clockwise direction in order selectively to control manually the position of the operating shaft 139 of the program selector switch 131 through the control rod 133. Finally, indicia is carried upon the skirt 142 of the control dial 130, that is correlated with respect to the control positions of the program selector switch 131, and cooperates with an index

pointer 142' secured to the top wall 21. Also, the program selector switch 131 comprises a timer motor and reduction gearing, not shown, whereby the operating shaft 139 thereof may be rotated further in the clockwise direction upon a time controlled basis.

The construction and arrangement of the inlet valve mechanism 112 and the program selector switch 131 are not disclosed in detail in the interest of brevity, as these devices are disclosed in the copending application of Walter P. McCarty, Serial No. 122,321, filed October 19, 1949.

Referring now to Figs. 5 and 6, the fluid drive unit 200 there illustrated is operatively associated with the electric drive motor 201 of the reversible rotor type provided with the operating or drive shaft 202. The motor 201 is mounted upon the frame 30 by an arrangement including a plurality of bolts 204 so that the drive shaft 202 occupies a substantially vertical position. The drive shaft 202 extends well above the upper end of the motor 201 and the frame 30 and has rigidly secured thereto a fixture 205 that is arranged to provide the two V-belt pulleys 206 and 207 respectively carrying the two V-belts 208 and 209. The fixture 205 is rigidly secured to the drive shaft 202 by an arrangement including a set screw 210 arranged in a threaded opening provided in a sleeve 211 carried on the lower end thereof. The upper end of the fixture 205 carries a sleeve 212 that terminates in an outwardly extending annular flange 213.

The fluid drive unit 200 is mounted upon the extreme upper end of the drive shaft 202 and upon the flange 213 and comprises the hollow casing 214 including lower and upper sections 215 and 216 hermetically sealed together. The lower portion of the casing 215 provides the V-belt pulley 217 that receives the associated V-belt 218. The hollow upper casing section 216 provides a substantially annular chamber 219 therein; and a substantially annular head 220 is arranged within the chamber 219 and rigidly secured to the extreme upper end of the drive shaft 202 by an arrangement including a threaded connection 221. The lower casing section 215 has a substantially centrally disposed opening therein through which the upper end of the drive shaft 202 projects, which opening terminates in an upstanding annular sleeve 222, the head 220 being provided with a downwardly projecting annular sleeve 223 formed integral therewith and projecting into the sleeve 222. The sleeves 222 and 223 are arranged in spaced-apart relation and are separated by an interposed bearing sleeve 224, the bearing sleeve 224 being frictionally secured to the interior surface of the opening provided in the sleeve 222. A recess 225 is formed in the lower portion of the lower casing section 215 within the pulley 217 and receives an anti-friction bearing element provided with upper and lower races 226 and 227. The lower race 227 is directly supported upon the adjacent upper surface of the flange 213 provided on the fixture 205, and the upper race 226 engages the lower end of the lower casing section 215, as well as the lower end of the bearing sleeve 224, the races 226 and 227 being supported in spaced-apart relation by a plurality of circumferentially spaced-apart balls 228. A centrally disposed recess is provided in the upper portion of the head 220, and a disk 229 is frictionally secured therein. Further, a centrally disposed threaded opening is provided in the upper portion of the upper casing section 216 and receives a threaded member 230 positioned

above the disk 229, a thrust ball 231 being arranged between the lower end of the threaded member 230 and the disk 229. The lower bearing arrangement, including the balls 228, and the upper bearing arrangement, including the ball 231, positively locate the casing 214 with respect to the head 220 and permit free rotation of the drive shaft 202 and the head 220 in the chamber 219 independently of the casing 214.

Further, a substantially centrally disposed annular reservoir 232 is formed in the lower casing section 215 below the head 220 and surrounding the sleeve 222, which reservoir 232 contains a quantity or body of fluid 233, such, for example, as a quantity of oil or other hydraulic medium. The upper level of the body of fluid 233 is disposed slightly below the junction between the lower and upper casing sections 215 and 216 so that the head 220 is disposed above and normally entirely out of contact with the body of fluid 233 arranged in the reservoir 232. The lower casing section 215 carries a plurality of circumferentially spaced-apart main driven blades 234 disposed exteriorly of the reservoir 232 and communicating therewith; and likewise the head 220 carries a plurality of circumferentially spaced-apart main drive blades 235 disposed above and exteriorly of the reservoir 232 and cooperating with the main driven blades 234. Thus the drive blades 235 carried by the head 220 are disposed above and out of contact with the driven blades 234 carried by the lower casing section 215, a narrow annular space 236 being provided between the sets of main blades 234 and 235. The arrangement described above permits free rotation of the head 220 and the drive blades 235 carried thereby with respect to the lower casing section 215 and the driven blades 234 carried thereby.

Finally, the fluid drive unit 200 comprises a direction-responsive starting arrangement including two substantially diametrically positioned start mechanisms 240 carried by the head 220 above and adjacent to the body of fluid 233 disposed in the reservoir 232. Preferably, the mechanisms 240 are identical, each comprising a fixture 241 provided with a body secured directly to the adjacent surface of the head 220 by a pair of screws 242, and a pair of spaced-apart depending arms 243 carrying a pivotally mounted start blade 244. The mechanism 240 is disposed in an offset position with respect to the center line of the drive shaft 202 and the center of the head 220; and the start blade 244 carries a depending counterbalance or weight 245 on the rear end thereof, the front end of the start blade 244 normally being disposed somewhat above the level of the body of fluid 233 provided in the reservoir 232. Specifically, the start blade 244 is pivoted intermediate the ends thereof upon a pair of oppositely directed trunnions 246 supported in cooperating bearing openings 247 provided in the arms 243 of the fixture 241. Thus when the drive shaft 202 is at rest, the start blade 244 occupies a substantially horizontal position, the counterbalance 245 pivoting the start blade 244 to the position noted about the trunnions 246 in order to insure that the front end of the start blade 244 is out of contact with the body of fluid 233 provided in the reservoir 232.

Considering now the operation of the fluid drive unit 200 when rotation of the drive shaft 202 is initiated in the counterclockwise direction, as viewed from the top of the unit 200, the head 220 moves toward the right in Fig. 6, and the impulse that is transmitted from the head 220

11

through the fixture 241 and the trunnions 246 to the start blade 244 causes the start blade 244 to be pivoted in the clockwise direction, as viewed in Fig. 6. This pivotal movement of the start blade 244 is brought about primarily by the inertia of the weight 245, the center of gravity of the weight 245 being disposed below the trunnions 246. When the start blade 244 is thus pivoted in the clockwise direction, as viewed in Fig. 6, the front end thereof dips into the body of fluid 233 provided in the reservoir 232, whereby the start blade 244 is pivoted further in the clockwise direction into a substantially vertical position about the trunnions 246, as indicated by the dotted lines in Fig. 6. The start blade 244 is restrained, when it is at rest, in its substantially horizontal normal position by a stop 248 extending between the arms 243 of the fixture 241; and the start blade 244 is restrained, when it is moved in the counterclockwise direction, as viewed from the top of the unit 200, into its substantially vertical operated position by a stop 249 depending from the body of the fixture 241. When the start blade 244 thus occupies its substantially vertical operated position and is rotated in the counterclockwise direction, as viewed from the top of the unit 200, the front end thereof catches the fluid contained in the reservoir 232 and splashes or deflects it outwardly away from the center line of the rotating drive shaft 202 and into the drive blades 235 and the space 236 disposed between the drive blades 235 and the driven blades 234. In order positively to insure that the fluid contained in the reservoir 232 is directed outwardly, as described above, each of the start mechanisms 240 is mounted at a slight angle with respect to a radius of the head 220 extending to the center line of the drive shaft 202. When the fluid contained in the reservoir 232 is thus directed into the space 236 and between the blades 235 and 234, the drive blades 235 exert a torque upon the driven blades 234, whereby rotation of the casing 214 is initiated. When rotation of the casing 214 is thus initiated the fluid contained in the reservoir 232 is flung outwardly by the centrifugal force into the space 236, thereby further insuring the drive relationship between the blades 235 and 234. Accordingly the casing 214 is gradually accelerated and ultimately rotates at a speed somewhat below that of the head 220 in view of the fact that there is always some slippage between the blades 235 and 234. Accordingly, when rotation of the drive shaft 202 is initiated in the counterclockwise direction, as viewed from the top of the unit 200, rotation of the casing 214, and consequently the pulley 217 carried thereby, is initiated, whereby rotation of the pulley 217 is gradually accelerated to a speed somewhat below that of the head 220 carried by the drive shaft 202.

Subsequently when operation of the motor 201 is arrested, rotation of the drive shaft 202 in the counterclockwise direction, as viewed from the top of the unit 200, is gradually decelerated, whereby the fluid contained within the casing 214 ultimately falls back by the action of gravity into the reservoir 232. When operation of the motor 202 is thus arrested, rotation of the unit 200 stops shortly thereafter by virtue of the connected loads upon the pulleys 204, 207 and 217, in an obvious manner; whereby the start blades 244 of the start mechanisms 240 are returned to their normal positions by the weights 245.

12

On the other hand, when rotation of the drive shaft 202 is initiated in the clockwise direction, as viewed from the top of the unit 200, the head 220 moves toward the left in Fig. 6, and the impulse that is transmitted through the arms 243 of the fixture 241 and the trunnions 246 to the start blade 244 is such that the weight 245 tends to pivot the start blade 244 further in the counterclockwise direction, as viewed in Fig. 6. However, further pivotal movement of the start blade 244 in the counterclockwise direction is prevented by the stop 248 carried by the arms 243 of the fixture 241, whereby the start blade 244 remains in its normal position. Accordingly, when rotation of the drive shaft 202 is initiated in the clockwise direction, as viewed from the top of the unit 200, the start blades 244 of the start mechanisms 240 remain in their normal positions, whereby the body of fluid 233 contained in the reservoir 232 is not disturbed and consequently the drive blades 235 are rotated freely with respect to the driven blades 234 and rotation of the head 220 is not transmitted to the casing 214.

In view of the foregoing description of the mode of operation of the unit 200, it will be understood that it is direction-responsive and that power is transmitted from the motor 201 to the pulley 217 carried by the casing 214 only in the event the drive shaft 202 is rotated in the counterclockwise direction, as viewed from the top of the unit 200. Accordingly, it will be appreciated that the load that is connected to the pulley 217 carried by the casing 214 may be selectively rotated through the V-belt 218 dependent upon the direction of rotation of the drive shaft 202. On the other hand, since the fixture 205 is rigidly secured to the drive shaft 202, the pulleys 206 and 207 drive the connected loads through the respective V-belts 208 and 209 when the drive shaft 202 is rotated in either direction.

Referring now to Figs. 7 and 8, the modified form of the fluid drive unit 300 there illustrated is operatively associated with the electric drive motor 201 of the reversible rotor type provided with the operating or drive shaft 202. The motor 201 is mounted upon the frame 30 by an arrangement including a plurality of bolts 204 so that the drive shaft 202 occupies a substantially vertical position. The drive shaft 202 extends well above the upper end of the motor 201 and the frame 30 and has rigidly secured thereto the fixture 205 that is arranged to provide the two V-belt pulleys 206 and 207 respectively carrying the two V-belts 208 and 209. The fixture 205 is rigidly secured to the drive shaft 202 by the arrangement including the set screw 210 arranged in the threaded opening provided in the sleeve 211 carried on the lower end thereof. The upper end of the fixture 205 carries the sleeve 212 that terminates in the outwardly extending annular flange 213.

The fluid drive unit 300 is mounted upon the extreme upper end of the drive shaft 202 and upon the flange 213 and comprises component elements 314 to 336, inclusive, respectively corresponding to the elements 214 to 236, inclusive, of the fluid drive unit 200 described above, which elements 314 to 336, inclusive, are now again enumerated in the interest of brevity.

Finally, the fluid drive unit 300 comprises a direction-responsive starting arrangement including two substantially diametrically positioned start mechanisms 340 of modified construction and arrangement and carried by the head 320

13

above and adjacent to the body of fluid 333 disposed in the reservoir 332.

Preferably the mechanisms 340 are identical, each comprising a fixture 341 provided with a body secured directly to the adjacent surface of the head 320 by a pair of screws 342, and a pair of spaced-apart depending arms 343 carrying a pivotally mounted start blade 344. The mechanism 340 is disposed in an offset position with respect to the center line of the drive shaft 302 and the center of the head 320, and the start blade 344 carries a small depending counterbalance or weight 345 on the rear end thereof, the front end of the start blade 344 normally being projected into the body of fluid 333 provided in the reservoir 332. Specifically, the start blade 344 is pivoted intermediate the ends thereof upon a pair of oppositely directed trunnions 346 supported in cooperating bearing openings 347 provided in the arms 343 of the fixture 341. Thus when the drive shaft 202 is at rest the start blade 344 occupies a substantial vertical normal position, the counterbalance 345 permitting the start blade 344 to pivot to the position noted about the trunnions 346 in order to insure that the front end of the start blade 344 is immersed in the body of fluid 333 provided in the reservoir 332.

Considering now the operation of the fluid drive unit 300 when rotation of the drive shaft 202 is initiated in the counterclockwise direction, as viewed from the top of the unit 300, the head 320 moves toward the right in Fig. 8, and the impulse that is transmitted from the head 320 through the fixture 341 and the trunnions 346 to the start blade 344 causes the start blade 344 to exert a force upon the fluid contained in the reservoir 332 tending to rotate the start blade 344 in the clockwise direction, as viewed in Fig. 8.

However, further pivotal movement of the start blade 344 in the clockwise direction from its substantially vertical normal position is prevented by a stop 348 depending from the body of the fixture 341. When the start blade 344 thus occupies its substantially vertical normal position and is rotated in the counterclockwise direction, as viewed from the top of the unit 300, the front end thereof catches the fluid contained in the reservoir 332 and splashes or deflects it outwardly away from the center line of the rotating drive shaft 302 and into the drive blades 335 and the space 336 disposed between the drive blades 335 and the driven blades 334. In order positively to insure that the fluid contained in the reservoir 332 is directed outwardly, as described above, each of the start mechanisms 340 is mounted at a slight angle with respect to a radius of the head 320 extending to the center line of the drive shaft 202. When the fluid contained in the reservoir 332 is thus directed into the space 336 and between the blades 335 and 334, the drive blades 335 exert a torque upon the driven blades 334, whereby rotation of the casing 314 is initiated. When rotation of the casing 314 is thus initiated the fluid contained in the reservoir 332 is flung outwardly by the centrifugal force into the space 336, thereby further insuring the drive relationship between the blades 335 and 334. Accordingly, the casing 314 is gradually accelerated and ultimately rotates at a speed somewhat below that of the head 320 in view of the fact that there is always some slippage between the blades 335 and 334. Accordingly when rotation of the drive shaft 202 is initiated in the counterclockwise di-

14

rection, as viewed from the top of the unit 300, rotation of the casing 314 and consequently the pulley 317 carried thereby is initiated, whereby rotation of the pulley 317 is gradually accelerated to a speed somewhat below that of the head 320 carried by the drive shaft 202.

Subsequently when operation of the motor 201 is arrested, rotation of the drive shaft 202 in the counterclockwise direction, as viewed from the top of the unit 300, is gradually decelerated, whereby the fluid contained within the casing 314 ultimately falls back by the action of gravity into the reservoir 332. When operation of the motor 201 is thus arrested, rotation of the unit 300 stops shortly thereafter by virtue of the connected loads upon the pulleys 206, 207 and 217, in an obvious manner, whereby the start blades 344 of the start mechanisms 340 are returned to their normal positions due to the fact that in each start blade 344 the center of gravity is disposed in the front end thereof.

On the other hand, when rotation of the drive shaft 202 is initiated in the clockwise direction as viewed from the top of the unit 300, the head 320 moves toward the left in Fig. 8, and the impulse that is transmitted through the arms 343 of the fixture 341 and the trunnions 346 to the start blade 344 causes the front end of the start blade 344 to drag out of the body of fluid 333 contained in the reservoir 332, whereby the start blade 344 is pivoted in the counterclockwise direction, as viewed in Fig. 8, into its operated position indicated by the dotted lines. Further, the impulse that is transmitted to the start blade 344 in this case also assists in the pivotal movement of the start blade 344 from its substantially vertical normal position to its inclined operated position. When the start blade 344 is thus operated into its inclined operated position the front end thereof is disposed somewhat above the level of the body of fluid 333 disposed in the reservoir 332 and out of contact therewith. Accordingly, when rotation of the drive shaft 202 is initiated in the clockwise direction, as viewed from the top of the unit 300, the start blades 344 of the start mechanisms 340 are immediately pivoted from their normal positions into their operated positions, whereby the body of fluid 333 contained in the reservoir 332 is not substantially disturbed and consequently the drive blades 335 are rotated freely with respect to the driven blades 334 and rotation of the head 320 is not transmitted to the casing 314.

In view of the foregoing description of the mode of operation of the unit 300, it will be understood that it is direction-responsive and that power is transmitted from the motor 201 to the pulley 217 carried by the lower casing section 315 only in the event the drive shaft 202 is rotated in the counterclockwise direction, as viewed from the top of the unit 300. Accordingly, it will be appreciated that the load that is connected to the pulley 217 carried by the lower casing section 315 may be selectively rotated through the V-belt 218 dependent upon the direction of rotation of the drive shaft 202. On the other hand, since the fixture 205 is rigidly secured to the drive shaft 202, the pulleys 206 and 207 drive the connected loads through the respective V-belts 208 and 209 when the drive shaft 202 is rotated in either direction.

The construction and arrangement of the fluid drive units 200 and 300 are disclosed and claimed in the copending divisional application of John C. Sharp, Serial No. 317,561, filed October 29, 1952,

In view of the foregoing descriptions of the fluid drive units 206 and 300, it will be understood that either of these embodiments may be employed as the fluid drive unit in the machine 10 illustrated in Figs. 1 to 3, inclusive, of the drawings. Thus when the operating shaft 202 of the motor 201 is rotated in the counterclockwise direction, as viewed from the top of the machine 10, the pulleys 206 and 207 rotate the respective pulleys 88 and 91 and the pulley 217 rotates the pulley 51; on the other hand, when the operating shaft 202 of the motor 201 is rotated in the clockwise direction, only the pulleys 206 and 207 rotate the respective pulleys 88 and 91.

Considering now the connection and arrangement of the electrical apparatus incorporated in the machine 10, and as illustrated in Fig. 4, the electric motor 201 is of the split-phase type and comprises a main or run winding 401 and an auxiliary or start winding 402, as well as a centrifugal switch 403 that is operatively connected to the rotor of the motor 201 and responsive to the speed of rotation thereof. Frequently a small phase splitting condenser is connected, in series with the start winding 402, as indicated at 402'. Specifically, the switch 403 is normally biased into its closed position and is operated into its open position in response to rotation of the rotor of the motor 201 in either direction at a speed of approximately one-half normal or above. Thus when operation of the motor 201 is initiated the rotor thereof is rotated in one direction or the other depending upon the direction of poling of the start winding 402, and when the rotor thereof reaches a speed of about one-half normal speed the switch 403 is automatically operated from its closed position into its open position in order to cut out of the circuit the start winding 402 in the usual manner. Also, as illustrated in Fig. 4, the program selector switch 131 comprises five individual control cams C1 to C5, inclusive, rigidly secured to the operating shaft 139 thereof, as well as five individual control switches S1 to S5, inclusive, respectively associated with the control cams C1 to C5, inclusive. Finally, the program selector switch 131 comprises a line switch LS that is operative between open and closed positions in accordance with longitudinal movement of the operating shaft 139 thereof. As disclosed in the previously mentioned McCarty application, the manually operable control dial 130 is capable of both rotary movement and limited longitudinal movement, whereby the corresponding movements are transmitted to the operating shaft 139 of the program selector switch 131. When the control dial 130 is rotated, the operating shaft 139 of the program selector switch 131 is rotated, whereby the control cams C1 to C5, inclusive, operate the individually associated control switches S1 to S5, inclusive. When the control dial 130 occupies its normal or depressed position, the operating shaft 139 of the program selector switch 131 occupies its lower position operating the line switch LS into its open position; and when the control dial 130 occupies its operated or raised position, the operating shaft 139 of the program selector switch 131 occupies its upper position operating the line switch LS into its closed position. Finally, the program selector switch 131 comprises a timer motor 404 and escapement mechanism, not shown, operatively connecting the timer motor 404 to the operating shaft 139.

Further, the machine 10 comprises a first electro-responsive relay 405 and a second electro-responsive relay 406, which relays 405 and 406

may be mounted upon the frame 30 within the machinery compartment 29, as illustrated in Fig. 2. Each of the relays 405 and 406 is of the slow-to-operate type, whereby the armature thereof is not operated until after the elapse of a predetermined time interval following energization of the winding thereof. This desired slow-to-operate characteristic of the relays 405 and 406 may be achieved by the provision of associated dashpots, not shown, operatively connected to the armatures thereof, or by the provision of heavy shunting windings on the magnetic core structures thereof. These details of construction are well understood, and the relays 405 and 406 are marked with the legend "SO" in order to indicate the slow-to-operate characteristic noted. Specifically, in Fig. 4 the solenoid 81 of the clutch mechanism 71, and the cold water solenoid 128 and the hot water solenoid 129 of the inlet valve mechanism 112 are illustrated. Finally, the electric control circuit comprises two terminals respectively indicated at "+" and "-", the "+" terminal being ungrounded in the machine 10, and the "-" conductor being grounded in the machine 10. Ultimately, the "+" and "-" terminals are operatively connected to a commercial source of 60 cycle 110 volts A. C. supply.

Considering now in greater detail the electrical connection and arrangement of the apparatus incorporated in the machine 10, and as illustrated in Fig. 4, the line switch LS as well as each of the control switches S1 to S4, inclusive, comprises two individual switch springs, while the control switch S5 comprises three individual switch springs, the relay 405 is provided with a single pair of contacts 407 controlled by the armature thereof; and the relay 406 is provided with five pairs of contacts 408 to 413, inclusive, controlled by the armature thereof. A supply conductor 414 is connected to the "-" terminal and to ground potential; while the "+" terminal is connected to one terminal of the line switch LS, the other terminal of the line switch LS being connected to a supply conductor 415. One of the switch springs of the control switch S1 is connected to the supply conductor 415, and the other of the switch springs thereof is connected to one terminal of the hot water solenoid 129, the other terminal of the hot water solenoid 129 being connected to the supply conductor 414. One of the switch springs of the control switch S2 is connected to the supply conductor 415, and the other of the switch springs thereof is connected to one terminal of the cold water solenoid 128, the other terminal of the cold water solenoid 128 being connected to the supply conductor 414. One of the switch springs of the control switch S3 is connected to the supply conductor 415, and the other of the switch springs thereof is connected to one terminal of the timer motor 404, the other terminal of the timer motor 404 being connected to the supply conductor 414. One of the switch springs of the control switch S4 is connected to the supply conductor 415, and the other of the switch springs thereof is connected to one terminal of the winding of the relay 405, the other terminal of the winding of the relay 405 being connected to the supply conductor 414. The intermediate switch spring of the control switch S5 is connected to the supply conductor 415, the lower switch spring thereof is connected to one terminal of the clutch solenoid 81, and the upper switch spring thereof is connected to one terminal of the winding of the relay 406.

The other terminal of the clutch solenoid 81 is connected to the supply conductor 414; and the other terminal of the winding of the relay 406 is connected to the supply conductor 414. One terminal of the run winding 401 of the motor 201 is connected to the supply conductor 414, and the other terminal of the run winding 401 is connected to one of the contacts 407 controlled by the armature of the relay 405, as well as to one of the contacts 413 controlled by the armature of the relay 406 and to the upper spring that is controlled by the armature of the relay 406. One terminal of the start winding 402 of the motor 201 is connected to one of the contacts 408 and to one of the contacts 412 controlled by the armature of the relay 406; and the other terminal of the start winding 402 is connected to one contact of the switch 403. The other contact of the switch 403 is connected to one of the contacts 409 and to one of the contacts 411 controlled by the armature of the relay 406; and the intermediate spring that is controlled by the armature of the relay 406 is connected to the supply conductor 414.

As previously explained, the program selector switch 131 is of the combination manually controlled and automatic timer controlled type, whereby the operating shaft 139 thereof may be rotated either by the manually operable control dial 130 or by the timer motor 404. The program selector switch 131 comprises an "off" position, a "hot fill" position, a "warm fill" position and a "cold fill" position, as well as a plurality of "control" positions; and the manually operable control dial 130 comprises corresponding and coordinate positions. In the operation of the machine 10 when the manually operable control dial 130 occupies its "off" position the control switches S1 to S5, inclusive, occupy their open positions as illustrated in Fig. 4; and when the control dial 130 occupies its normal depressed position, the line switch LS occupies its open position as illustrated in Fig. 4.

In order to fill the tub 49 with hot water the user merely rotates the control dial 130 into its "hot fill" position and then lifts it, whereby the required circuits are closed to effect filling of the tub 49 with hot water. After the tub 49 has been filled with hot water the user again depresses the control dial 130 in order to operate the line switch LS into its open position so as to interrupt the preselected circuits mentioned. Of course, the filling of the tub 49 with warm water or with cold water proceeds in a substantially identical manner, the control dial 130 first being rotated into its corresponding position and then lifted, and thereafter again depressed after the filling of the tube 49. After the tub 49 has been filled with hot or warm or cold water as required by the character of the fabrics to be washed, the control dial 130 is then rotated into its first "control" position and again lifted, whereby an automatic cycle of operation is initiated under the control of the timer motor 404. More particularly, the timer motor 404 rotates the control dial 130 further in the clockwise direction, as viewed from the top of the machine 10 back into its "off" position, whereby the program selector switch 131 is rotated through its various "control" positions and thence back into its "off" position. When the program selector switch 131 is thus rotated through its various "control" positions, an automatic timed cycle of the apparatus incorporated in the machine 10 is carried out, whereby the machine 10 effects a washing operation followed by

a wash water extracting operation and then a rinsing operation followed by a rinse water extracting operation, whereupon further operation of the machine 10 is arrested.

In order to illustrate an example of the manual controls that may be performed by the user of the machine 10 in conjunction with the electric circuit illustrated in Fig. 4, let it be assumed that the machine 10 is at rest, and that it is desired to fill the tub 49 with hot water, the user rotates the control dial 130 in the clockwise direction into its "hot fill" position, the segment between 10° and 25° thereon, and then lifts the control dial 130. When the control dial 130 is thus rotated into its "hot fill" position, as noted above, the control cam C1 closes the control switch S1 to effect selection of the circuit of the hot water solenoid 129; and the control cam C4 closes the control switch S4 to effect selection of the circuit of the relay 405; and when the control dial 130 is lifted the line switch LS is closed in order to complete the preselected circuits noted. Specifically, the hot water solenoid 129 is energized, whereby the inlet valve mechanism 112 is operated to supply hot water from the hot water inlet conduit 120 into the tub 49. Also the winding of the relay 405 is energized, whereby the latter relay operates shortly thereafter, it being of the slow-to-operate type. Upon operating, the relay 405 completes, at the contacts 407, a circuit for energizing the run winding of the motor 201 across the supply conductors 414 and 415; and completes, at the contacts 407, a multiple circuit, including the contacts 409 and 412 and the switch 403, for poling the start winding 402 of the motor 201 in a first direction across the supply conductors 414 and 415. When the run winding 401 is thus energized and the start winding 402 is thus poled, operation of the motor 201 is initiated, whereby the rotor of the motor 201 is rotated in the clockwise direction, as viewed from the top of the machine 10. When the motor 201 is thus rotated in the clockwise direction the pulleys 84 and 85 effect rotation of the associated pulleys 206 and 207; however, the direction-responsive fluid drive unit 200 does not effect rotation of the pulley 217. Accordingly, the pump 86 and the motion translating mechanism 73 are operated; however, the tub 49 is not rotated. While operation of the motion translating mechanism 73 is initiated, the agitator 67 is not operated since the clutch mechanism 77 is declutched at this time. Thus the operating drain pump 86 is effective to discharge to the exterior any water accumulating in the tub compartment 28 should the tub 49 be filled to overflowing at this time. When the rotor of the motor 201 gains approximately one half normal speed, the speed-responsive switch 403 is operated to its open position interrupting the circuit for poling the start winding 402; however, rotation of the rotor of the motor 201 in the clockwise direction continues by virtue of the completed circuit for energizing the run winding 401 thereof at this time, and of course, the rotor of the motor 201 is accelerated on into full normal speed. When the desired quantity of hot wash water has been admitted to the tub 49, the user merely depresses the control dial 130 effecting opening of the line switch LS, whereby the hot water solenoid 129 is de-energized and the winding of the relay 405 is de-energized. When the hot water solenoid 129 is thus de-energized, the inlet valve mechanism 112 is restored to its normal position cutting off the supply of hot water to the tub 49; and when the winding of the relay 405 is thus de-energized,

the latter relay restores immediately to interrupt, at the contacts 407, the circuit for energizing the run winding 401 of the motor 201 in order to arrest further operation thereof.

In view of the foregoing description of the manner in which the user manually controls filling of the tub 49 with hot water, it will be understood that the tub 49 may be filled in a substantially identical manner with either warm water or cold water, the user merely rotating the control dial 130 into its corresponding position and lifting it. Specifically, when the control dial 130 is rotated into its "warm fill" position, the segment between 25° and 40°, the control cams C1 and C2 respectively operate the control switches S1 and S2 into their closed positions in order to preselect both the circuit of the hot water solenoid 129 and the circuit of the cold water solenoid 128, whereby both of the solenoids mentioned are subsequently energized upon closure of the line switch LS as a consequence of lifting the control dial 130. Similarly, when the control dial 130 is rotated into its "cold fill" position, the segment between 40° and 55°, the control cam C2 operates the control switch S2 into its closed position in order to preselect the circuit of the cold water solenoid 128, whereby the solenoid mentioned is subsequently energized upon closure of the line switch LS as a consequence of lifting the control dial 130.

When the control dial 130 is rotated into its "hot fill" position or into its "warm fill" position or into its "cold fill" position, the control cam C4 operates the control switch S4 into its closed position in order to preselect the circuit of the winding of the relay 405 so that operation of the motor 201 is initiated upon subsequent closure of the line switch LS as a result of lifting the control dial 130 and so that the rotor of the motor 201 is rotated in the clockwise direction, as viewed from the top of the machine 10. This arrangement positively insures operation of the motor 201 at this time and operation of the drain pump 86 so as to prevent flooding of the laundry room as a result of overflowing of the water from the tub 49 into the tub compartment 28 formed in the upper casing 12 should the user inadvertently permit the control dial 130 to remain in its raised position after a filling operation has been completed.

After the user has affected manual control of the circuit network in the manner described above in order to cause filling of the tub 49 with hot or warm or cold water as required, she may initiate the automatic cycle of the machine 10 merely by rotating the control dial 130 into its first "control" position, beginning slightly beyond the 55° position, and again lifting the control dial 130 after she has placed the clothes and the detergent in the tub 49 and closed the cover 107. When the control dial 130 is rotated into its first "control" position, the control cam C1 and C2 positively insure operation of the respective control switches S1 and S2 into their open positions so as to prevent control of the hot water solenoid 129 and the cold water solenoid 128 at this time. Also the control cam C3 operates the control switch S3 into its closed position in order to preselect the circuit of the timer motor 404. Further, the control cam C4 operates the control switch S4 into its closed position to preselect the circuit of the winding of the relay 405. Finally, the control cam C5 operates the control switch S5 to close the contacts between the lower and intermediate springs thereof in order to preselect the clutch solenoid 81 of the clutch mech-

anism 77. When the control dial 130 is then lifted the preselected circuits noted are completed at the line switch LS. Specifically, the timer motor 404 operates to effect further rotation of the operating shaft 139 of the program selector switch 131 and the control dial 130 in the clockwise direction through the various "control" positions thereof and ultimately back into the "off" positions thereof. The relay 405 operates shortly thereafter to effect operation of the motor 201, whereby the rotor thereof is rotated in the clockwise direction as viewed from the top of the machine 10. The clutch solenoid 81 operates to effect clutching of the elements 78 and 79 of the clutch mechanism 77 in order to bring about oscillation of the shaft 63 from the motion translating mechanism 73 that is driven from the motor 201 through the pulleys 207 and 91 by the V-belt 209. The oscillating shaft 63 effects oscillation of the agitator 67 in the tub 49 in order to initiate the washing operation of the machine 10.

The first "control" position of the control dial 130 extends from the 55° position thereof to the 170° position thereof covering an intervening segment of 115° which corresponds to a time interval of 11½ minutes since the program selector switch 130 is of the Mallory drive type and steps the operating shaft 139 thereof and the control dial 130 in the clockwise direction 5° each ½ minute; whereby 10° of rotation of the program selector switch 131 and the control dial 130 correspond to a time interval of 1 minute. Accordingly, when the user sets the control dial 130 into the first "control" position thereof she brings the desired washing time on the skirt 142 thereof into registry therewith with the associated index pointer 142'. Thus it will be understood that in the event a full washing time interval of 11½ minutes is desired that the control dial 130 is rotated slightly past the 55° position thereof before it is lifted. On the other hand, for example, in the event a shorter washing time interval of five minutes is desired, the control dial 130 is rotated to the 120° position thereof before it is lifted. Thus the washing time interval is manually adjustable between 11½ minutes and ½ minute at any time interval of ½ minute therebetween.

The washing operation of the machine 10 continues during the preset washing time interval and until the program selector switch 131 is rotated into its 170° position, whereupon the control cam C4 operates the control switch S4 into its open position, and the control cam C5 operates the control switch S5 to open the contacts between the lower and intermediate springs thereof and to close the contacts between the intermediate and upper springs thereof. When the control switch S4 is operated into its open position the relay 405 immediately restores in order to arrest operation of the motor 201. When the control switch S5 is operated to open the contacts between the lower and intermediate springs thereof, the clutch solenoid 81 is de-energized, whereby the clutch mechanism 77 is returned to its normal de-clutched position, the clutch elements 78 and 79 being disengaged. When the control switch S5 is operated to close the contacts between the intermediate and upper springs thereof, the circuit for energizing the winding of the relay 406 is completed, whereby the relay 406, being of the slow-to-operate type, operates shortly thereafter. The time interval between the restoration of the re-

lay 405 and the operation of the relay 406 is sufficient to permit rotation of the rotor of the motor 201 to be arrested. Upon operating, the relay 406 completes, at the contacts 413, the alternative circuit for energizing the run winding 401 of the motor 201; interrupts, at the contacts 409 and 412, points in the previously traced circuit for poling the start winding 402 of the motor 201; and completes, at the contacts 408 and 411, the alternative circuit for poling the start winding 402. The circuit for poling the start winding 402 that is completed at this time via the speed-responsive switch 403 is such that the start winding 402 is poled in a second or opposite direction with respect to the first direction previously mentioned. When the run winding 401 is thus energized and the start winding 402 is thus poled in the second direction mentioned, operation of the motor 201 is initiated, the rotor being rotated in the counterclockwise direction, as viewed from the top of the machine 10.

When the rotor of the motor 201 gains approximately one half normal speed, the switch 403 is operated to open the start winding 402 in the usual manner, whereby the run winding 401 accelerates the rotor of the motor 201 on into its normal speed. At this time when the rotor of the motor 201 is rotated in the counterclockwise direction, the fluid drive unit 200 is operated to effect the transmission of power therethrough from the motor 201 to the sleeve 44 via the pulleys 217 and 51 and the V-belt 218. Accordingly, the sleeve 44, and consequently the tub 49, is rotated in the counterclockwise direction at this time, the rotation of the tub 49 being gradually accelerated to its full spinning speed by virtue of the slippage in the fluid drive unit 200 as previously explained. When the tub 49 is thus rotated the initial wash water contained therein is centrifuged therefrom through the openings 59 disposed just below the balance ring 56, the wash water being caught in the tub compartment 23 and drained through the fixture 94 into the drain pump 86 from which it is pumped to the exterior of the machine 10 through the drain conduit 95. The initial wash water is thus discharged from the tub 49 by the centrifugal forces, the clothes being retained therein by virtue of the overhanging flange 57 provided on the balance ring 56. The clothes in the tub 49 are thus spun for a time interval of 4 minutes in order to effect the substantially complete removal of the wash water therefrom, at which time the program selector switch 131 is rotated into its 210° position; whereby the control cams C1 and C2 effect closure of the respective switches S1 and S2 bringing about operation of the respective solenoids 129 and 128. When the solenoids 129 and 128 are thus operated, warm water is supplied via the inlet conduit 109 into the tub 49 while it is spinning in order to effect a warm water spinning rinsing action upon the contained clothes.

The program selector 131 is rotated into its 215° position 1/2 minute later, whereby the control cams C1 and C2 effect operation of the respective switches S1 and S2 into their open positions so as to de-energize the respective solenoids 129 and 128 for the purpose of interrupting the supply of warm water to the spinning tub 49. The program selector 131 is rotated into its 220° position 1/2 minute later, whereby the control cam C2 effects operation of the switch S2 into its closed position effecting operation of the cold water solenoid 129 and the consequent

supply of cold water from the inlet conduit 109 into the spinning tub 49 in order to effect a cold water spinning rinsing action upon the contained clothes. The program selector 131 is rotated into its 225° position 1/2 minute later, whereby the control cam C5 operates the switch S5 to move the intermediate spring thereof to a center position disengaging both the associated upper and lower springs so as to interrupt the circuit for energizing the winding of the relay 406 without completing the circuit for energizing the clutch solenoid 81. Accordingly, the relay 406 restores, interrupting, at the contacts 413, the circuit for energizing the run winding 401 of the motor 201.

15 Also, the relay 406 interrupts, at the contacts 403 and 411, further points in the circuit for poling the start winding 402 in the second direction previously noted and reprepares, at the contacts 409 and 412 points, in the circuit for poling the start winding 402 in the first direction previously noted. Accordingly, at this time, rotation of the rotor of the motor 201 in the counterclockwise direction as viewed from the top of the machine 10, is arrested.

20 Also at this time the control cam C4 operates the control switch S4 into its closed position in order to effect reoperation of the relay 405 shortly thereafter, whereby operation of the motor 201 is again initiated. As previously explained, upon operating, the relay 405 effects rotation of the rotor of the motor 201 in the clockwise direction, as viewed from the top of the machine 10. Thus at this time rotation of the tub 49 is arrested in order to terminate the cold water spinning rinsing action on the clothes contained therein. The program selector switch 131 is rotated into its 260° position 3 1/2 minutes later, whereby the tub 49 is filled to overflowing during the time interval mentioned, the cold water supplied from the inlet conduit 109 into the tub 49 overflows therefrom via the openings 59 provided below the balance ring 56.

25 In the 260° position of the program selector switch 131 the control cam C5 operates the control switch S5 to close the contacts between the lower and intermediate springs thereof in order to effect reoperation of the clutch solenoid 81, whereby the actuator 67 is again oscillated for the purpose of initiating a deep cold water overflow rinsing action upon the clothes contained in the tub 49. This deep cold water overflow rinsing action continues for a time interval of 1 1/2 minutes; at which time the program selector switch 131 is rotated into its 285° position, 30 whereby the control cam C2 effects operation of the control switch S2 into its open position so as to bring about de-energization of the cold water solenoid 128 and the consequent interruption of the supply of cold water from the inlet conduit 109 into the tub 49. After the supply of cold water into the tub 49 is thus cut off, operation of the actuator 67 continues for a time interval of 1/2 minute and until the program selector switch 131 is rotated into its 290° position 35 in order positively to insure that the excess quantity of cold water contained in the tub 49 is overflowed therefrom prior to initiating a final spinning extracting operation of the tub 49, as explained below.

40 When the program selector switch 131 is rotated into its 290° position, the control cam C4 operates the control switch S4 into its open position in order to effect restoration of the relay 405 and consequently operation of the motor 201. 45 Also, the control cam C5 operates the control

switch S5 to open the contacts between the lower and intermediate springs thereof and to close the contacts between the intermediate and upper springs thereof so as to deenergize the clutch solenoid 81 and to re-energize the winding of the relay 406. The clutch mechanism 77 is restored to its declutched position in order to arrest operation of the agitator 67, and the rotor of the motor 201 is rotated in the counterclockwise direction in order to effect spinning of the tub 49 through the fluid drive unit 200, in the manner previously explained. When rotation of the tub 49 is thus initiated, a final rinse water extracting operation of the machine 10 is initiated. The tub 49 continues to spin during a time interval of 7 minutes and until the program selector switch 131 is rotated into its 360° or 0° position constituting its "off" position. During this spinning operation of the tub 49 the cold rinse water contained in the tub 49 and in the clothes therein is extracted, whereby at the termination of the final rinse water extracting operation, the clothes contained in the tub 49 contain only a nominal amount of water, usually each pound of clothes containing approximately one pound of water. At this time the program selector switch 131 and the control dial 130 occupy their coordinate "off" positions indicating that the automatic cycle of the machine 10 has been completed; and all electric circuits are interrupted. Specifically, when the program selector switch 131 is rotated back into its "off" position the control cam C3 operates the control switch S3 to its open position in order to arrest operation of the timer motor 404. Also the control cam C5 operates the control switch S5 to move the intermediate spring into a center position in order to open the contacts between the intermediate spring and the upper spring thereof without closing the contacts between the intermediate spring and the lower spring thereof so as to effect the restoration of the relay 406. Upon restoring, the relay 406 arrests operation of the motor 201; and at this time the cycle of operation of the machine 10 has been completed and the user may again depress the control dial 130 in order to effect operation of the line switch LS into its open position so as to interrupt a further common point in all of the electric control circuits. At this time the user may open the cover 107 and transfer the clothes contained in the tub 49 to a drier in order to prepare the clothes for ironing in the usual manner.

In view of the foregoing explanation of the control of the machine 10 by the control dial 130 and the program selector 131, it will be understood that any one of the operations in the automatic cycle may be selectively repeated either before or after the completion of the cycle of operation of the machine 10 by first depressing the control dial 130, then rotating the control dial 130 into the "control" position corresponding to the desired operation, and then lifting the control dial 130, whereby operation of the machine 10 in the preselected operation in the automatic cycle is initiated. This facility is occasionally useful when it is desired to obtain a somewhat more thorough drying of a heavy load of fabrics in the form of a scatter rug, or the like. For instance, in this case, the final rinse water extracting operation of the machine 10 may be selectively repeated in order to obtain additional time intervals of 7 minutes of water extracting operations. Of course, any of the other operations in the automatic cycle may be similarly re-

peated, and occasionally this facility is useful where it is particularly desired to obtain a washing operation of longer than 11½ minutes and involving a particularly dirty fabric, such, for example, as work clothes. In this case, the user sets the control dial 130 for a full time interval of 11½ minutes and initiates operation of the machine 10 by lifting of the control dial 130. Thereafter, at the expiration of an appropriate 10 additional time interval, such, for example, as 10 minutes the control dial 130 is depressed and rotated through and back into the beginning of the first control position thereof, such that a time interval of 11½ minutes is again set; whereupon the control dial 130 is again lifted so that the machine 10 may proceed through its normal automatic cycle, as previously explained. In this example, the washing time of the machine 10 has been increased by 10 minutes in order 20 to produce a total washing time of 21½ minutes. Of course, operation of the machine 10 may be arrested at any time either during a manual filling operation or an operation thereof in its automatic control cycle merely by depressing the control dial 130; and thereafter further operation of the machine may be again initiated merely by lifting the control dial 130. This stop and start facility in response to the corresponding movements of the control dial 130 between its raised and depressed positions follows by virtue of the circumstance that the line switch LS occupies a master control or interlock position in the electric control network.

In the circuit control network the organization of the contacts controlled by the relays 405 and 406 comprises switching apparatus having an "off" position, when both of the relays 405 and 406 are restored, a "first run" position, when the relay 405 is operated, and a "second run" position, when the relay 406 is operated. This switching apparatus is operative from its "off" position into either one of its "run" positions, and from either one of its "run" positions through its "off" position into the other one of its "run" positions, the operation of the switching apparatus out of its "off" position being slow to insure slow-down of the rotor of the electric motor 201 in the event of reversal of the rotor of the motor 201.

50 In view of the foregoing it is apparent that there has been provided a semi-automatic clothes washing machine comprising an improved power transmission mechanism that is direction-responsive and a single drive motor of the reversible rotor type therefor, as well as an improved electric control network for selectively starting rotation of the rotor of the motor in either direction and for selectively reversing the direction of rotation of the rotor of the motor in order selectively 55 to control the operations of the machine in an automatic cycle including washing, wash water extracting, rinse and rinse water extracting operations.

60 While there has been described what is at present considered to be the preferred embodiment of the invention, it will be understood that various modifications may be made therein, and it is intended to cover in the appended claims all such modifications as fall within the true spirit 65 and scope of the invention.

70 What is claimed is:

75 1. In a clothes washing machine including an upstanding casing, an upstanding tub arranged in said casing and mounted for rotation, an upstanding agitator arranged in said tub and

mounted for oscillation, a water supply system communicating with said tub, said casing being arranged to catch water centrifuged from said tub incident to rotation thereof, and a drain conduit communicating with said casing; the combination comprising an electric motor provided with a reversible rotor, a fluid drive unit including a casing containing a body of fluid and a drive member and a driven member and means responsive to rotation of said drive member in one direction for coupling said drive member through said fluid to said driven member and responsive to rotation of said drive member in the opposite direction for uncoupling said drive member from said driven member, a first drive connection between said rotor and said drive member, a second drive connection between said driven member and said tub, means for selectively rotating said rotor in either direction in order selectively to effect rotation of said tub, motion translating mechanism including a drive element and a driven element and means responsive to rotation of said drive element in either direction for oscillating said driven element, a third drive connection between said rotor and said drive element, clutch mechanism arranged between and operatively connected to both said driven element and said agitator, and means for selectively operating said clutch mechanism in order selectively to effect oscillation of said agitator.

2. In a clothes washing machine including an upstanding casing, an upstanding tub arranged in said casing and mounted for rotation, an upstanding agitator arranged in said tub and mounted for oscillation, a water supply system communicating with said tub, said casing being arranged to catch water centrifuged from said tub incident to rotation thereof, and a drain conduit communicating with said casing; the combination comprising an electric motor provided with a reversible rotor, a fluid drive unit including a casing containing a body of fluid and a drive member and a driven member and means responsive to rotation of said drive member in one direction for coupling said drive member through said fluid to said driven member and responsive to rotation of said drive member in the opposite direction for uncoupling said drive member from said driven member, a first drive connection between said rotor and said drive member, a second drive connection between said driven member and said tub, means for selectively rotating said rotor in either direction

in order selectively to effect rotation of said tub, motion-translating mechanism operative to translate rotary motion into oscillatory motion, a third drive connection between said rotor and said motion-translating mechanism, clutch mechanism arranged between said motion-translating mechanism and said agitator, and means for selectively operating said clutch mechanism in order selectively to effect oscillation of said agitator.

10 3. The clothes washing machine combination set forth in claim 2, and further comprising a drain pump including a housing connected to said drain conduit and a part arranged in said housing and rotatable in either direction to draw water from said drain conduit into said housing and to discharge the water from said housing to the exterior, and a fourth drive connection between said rotor and said part.

15 4. The clothes washing machine combination set forth in claim 2, and further comprising interlock means for positively preventing simultaneous rotation of said rotor in said one direction and operation of said clutch mechanism.

JOHN C. SHARP.
